(57) **CLAIM**

The ornamental design for a multipurpose implement with a nubbed surface for kitchen use, as shown and described.

DESCRIPTION

FIG. 1 is a perspective view of our new design for multipurpose implement with a nubbed surface for kitchen use.

FIG. 2 is a front elevation view of the multipurpose implement of FIG. 1; the rear elevation view of the multipurpose implement of FIG. 1 is a mirror image of FIG. 2.

FIG. 3 is a first side elevation view of the apparatus of FIG. 1.

FIG. 4 is a second side elevation view of the apparatus of FIG. 1.

FIG. 5 is a third side elevation view of the apparatus of FIG. 1; and,

FIG. 6 is a fourth side elevation view of the apparatus of FIG. 1.

The broken lines forming the "X" and those around the perimeter on the face and back of the item represent stitching and are claimed. The dash-dot-dot-dash lines on the corner protrusion represent portions of the structure that form no part of the claim. The "KG" represents a trademark and is included for the purpose of illustrating environment. The "KG" forms no part of the claim.
